Inventor:

Solomon Dwight

UNITED STATES PATENT OFFICE.

SOLOMON DWIGHT, OF BYRON, ILLINOIS.

IMPROVEMENT IN CULTIVATORS.

Specification forming part of Letters Patent No. 31,305, dated February 5, 1861.

To all whom it may concern:

Be it known that I, SOLOMON DWIGHT, of Byron, in the county of Ogle, in the State of Illinois, have invented certain new and useful Improvements in Cultivators; and I do hereby declare that the following is a full and exact description thereof, reference being had to the accompanying drawings, and to the letters of reference marked thereon.

My invention relates to a novel method of constructing cultivators, particularly to the cultivation of corn; and my invention consists in certain novel features of construction in the apparatus, as will be hereinafter fully described.

To enable those skilled in the art to make and use my invention, I will proceed to describe the construction and operation of my improved cultivator, referring by letters to the accompanying drawings, forming part of this specification, and in which—

Figure 1 is a perspective view of my improved machine. Fig. 2 is a side elevation of the same. Fig. 3 is a rear elevation of the same. Fig 4 is a vertical longitudinal section at the line *x* *x* of Fig. 3. Fig. 5 is a detached view, in perspective, of one of the shields, (to be referred to particularly hereinafter;) and Fig. 6 is a view showing in perspective each of the cultivating-teeth.

In the different figures the same letter indicates the same part of the apparatus.

A is the main horizontal frame, which is formed out of the same piece of timber as the tongue *B* in the following manner, viz: A beam of suitable material and proper size is shaped during one half its length suitably to form the tongue *B*. The other half is sawed down and bent or straddled around a wedge-shaped piece, *D*, the timber being bound at the point where the bifurcation commences by a band of metal, *C*. The sides of arms of the frame *A*, after being bent round the piece *D*, (to which they are bolted,) are braced together by a cross-tie, *H*, secured at each end to the frame *A* by bolts *n n*. (See Fig. 1.) To the rear surface of this cross-tie *H* are bolted the vertical standards *G G*, which carry the rear cultivating-blades, *J*, while to the rear extremities of the frame-piece *A* are secured the standards *E E*, which carry the outer blades, *K K*, and the top ends of which are formed into the operator's handles *e e*. The said standards *E E*

are braced by a cross-piece, *F*, suitably secured at each end to said standards by bolts.

I I are two adjustable and removable shields, which are hung by their arms *i i* to the inner surface of the frame *A* and standards *G* in such manner as to be readily adjustable and removable, as will be presently more particularly explained.

The standards *E* and *G* are braced to frame *A* by rods *f* and *g*.

On the rear side of the wedged-shaped piece *D* is arranged a strap, *b*, which is held by a bolt-rod, *a*, passing vertically through said piece *E*, and to which strap the single-tree attachment for the team may be attached, whereby the draft is brought into the most desirable line.

It will be observed that in the upper end of each of the arms *i* of the shields *I* there are formed two holes, 1 and 2, (see Fig. 5,) the object of which is to admit of shifting the bolt which passes through either of said holes from one to the other to raise or lower the position of the shield *I* as circumstances may require.

In the cross-piece *H*, to which the standards *G* are secured, are formed two sets of holes. The said standards *G* are represented as bolted into one set of holes. The other set are marked 1 and 2. The object of this series of holes is to shift the position laterally of the standards *G*, to place them nearer together or farther apart, according to the condition of the corn being cultivated.

The cross-tie *H* is curved or arched out on its lower edge to allow it to pass freely over the tops of the stalks, which the machine straddles.

The general operation of my improved apparatus may be thus explained: The team being hitched in, and the inner teeth, *J J*, being adjusted to the proper distance apart, (by means of the adjustable standards *E*,) and the shields *I* being set to the proper height to suit the condition of the corn, the operator grasps the handles *e*, and governs the machine in the usual manner. The teeth *J* and *K*, acting combinedly, perfectly loosen and throw up around the roots of the stalks of corn the disintegrated particles of earth, while the shields act effectually to prevent the earth from smoothing the plants.

It will be understood that my improved

corn-cultivator may be employed to cultivate other plants, and that the shields I may under some conditions of use of the machine be entirely removed by simply taking out the bolts which secure the arms *i i* in the means already described.

The adjustment of the inner teeth or shares, J J, in the manner already explained, is of great utility, since it enables the operator to set the said teeth as near to or far from the stalks as their condition and growth require.

It will be seen that by taking a single piece of wood possessing sufficient elasticity and forming the main horizontal frame all of it, as described, the construction of the apparatus is rendered exceedingly simple, and at the same time very durable and strong.

Having described the construction and operation of my improved cultivator, what I claim therein as new, and desire to secure by Letters Patent, is—

The arrangement of the main frame A and tongue B of a single piece of timber, in combination with the retaining-strap C, shaping-block D, cross-brace H, and standards E, the whole arranged and operating as specified, for the purpose set forth.

In testimony whereof I have hereunto set my hand and affixed my seal this 17th day of November, 1860.

SOLOMON DWIGHT. [L. S.]
